UNITED STATES PATENT OFFICE.

CHARLES ELLIOT, OF SAN FRANCISCO, CALIFORNIA.

PURIFYING WATER FOR BOILERS.

SPECIFICATION forming part of Letters Patent No. 374,828, dated December 13, 1887.

Application filed July 22, 1887. Serial No. 245,011. (No model.)

To all whom it may concern:

Be it known that I, CHARLES ELLIOT, a citizen of the United States, residing at San Francisco, in the county of San Francisco and 5 State of California, have invented certain new and useful Improvements in Apparatus for Purifying Water for Boilers, of which the following is a specification.

My invention relates to improvements on the apparatus for purifying water for boilers patented to me February 6, 1883, and numbered 271,821, whereby the apparatus there shown is greatly simplified by dispensing with the check-valve in the overflow, having but one pipe for blow-off and feed-water supply, and other modifications, hereinafter described.

My invention consists of a closed settler which is placed inside the boiler. It has at one end an open stand-pipe, in which the water 20 stands above the level of that in the body of the settler, and at the other end a pipe leading out of the boiler. The feed-water is forced into the settler in boiler through one branch of this pipe, while the other branch is used to 25 blow off the settler. The outlet or overflow to let the water into the boiler extends down into the settler to trap the floating matter, while its outer end terminates above the level 30 of the water-line in the boiler, but below that of the open end of the stand-pipe. The diameter of the stand-pipe is that of the shortest diameter of the settler.

In the accompanying drawings, which illustrate my invention, Figure 1 is a view, partly 35 broken away, of my improved settler; and Fig. 2 is a view of the same when placed in an upright boiler.

A is the boiler.

B is the settler or body of the purifier.

40 C is the stand-pipe, of the full size of the tube forming the body of the settler. It is fastened directly to and forms part of the settler, but does not extend downward into it, so that no space is formed in the settler for the 45 steam to accumulate and blow out the water, as it does in all other purifiers of this description.

D is the pipe leading from the other end of the settler at or near its bottom, and having the branch E leading to the feed-water-supply 50 pump.

F is the blow-off branch of pipe D.

G is the feed-water-supply pump.

H is the outlet or overflow by which the water from the settler escapes into the boiler. Its inner end, as shown, descends below the 55 water-line a a in the settler, so as to trap the floating matter; b. Its outer end is above the level of the water-line x x in the boiler.

I are clamps by which the settler is held 50 in place.

J J are the boiler-tubes.

K K, Fig. 2, are the grate-bars.

In Fig. 2 the settler is shown placed in an upright boiler, in which case the upper extremity of the settler-body becomes the stand-pipe C; but the relations and operation of the different parts of the settler are identical in every respect with Fig. 1. Its operation is as follows: Water being fed into the settler through the feed-pipe E D, its impurities sink 70 or rise, as the case may be, and the heated water escapes into the boiler through the overflow free from all such impurities.

From this novel and simple construction of the settler many advantages arise. Owing to 75 the large size of the stand-pipe and the pressure of the column of water caused by its height above the settler-body, the introduction of cold water into the settler does not cause a concussion, dangerous alike to both boiler and 80 purifier and liable to burst the feed-pipe. The absence of any cavity or space in the settler for the accumulation of steam prevents the blowing over of the feed-water with its 85 impurities in the settler into the boiler. The opening of the overflow being above the water-line in the boiler, the water in the latter is not sucked or driven out through the settler whenever it is blown out, or the volume of water in the settler lessened from any cause. Whenever 90 the settler is blown out, the column of water in the stand-pipe causes the steam to blow through it from end to end, expelling all deposit and effecting a thorough cleansing. In introducing the feed-water into the boiler 95 it is compelled to flow the whole length of the settler, by which it becomes thoroughly heated and purified.

While I have shown the stand-pipe of the same size as that of the tube or box constituting the settler-body, that being the size which I prefer and which gives the best results, as far as I am now aware, this size may be varied within certain limits without departing from 100

the spirit of my invention, which consists in so shaping and attaching the stand-pipe to the body of the settler that no cavity shall be formed in the settler in which steam can accumulate, and in maintaining a head of water above the level of that in the body of the settler proper.

Having thus described my invention, what I claim as new, and desire to secure by Letters Patent, is—

1. An apparatus for purifying water within a boiler having a closed body, a stand-pipe, an overflow, and a combined feed and blow-off pipe, substantially as described.

2. The combination, with a closed settler having an overflow, of a stand-pipe placed upon the settler, as shown, by means of which the settler will be maintained full of water, a

feed-pipe for supplying feed-water to the settler, and means for blowing off the settler, substantially as described.

3. The combination of the settler, the stand-pipe, the overflow, and the pipe D, substantially as and for the purpose hereinbefore set forth.

4. The combination of settler B, stand-pipe C, overflow H, pipe D, and branches E and F, arranged substantially as hereinbefore set forth.

In testimony whereof I have affixed my signature in presence of two witnesses.

CHARLES ELLIOT.
